EXHAUST SYSTEM

Elihu N. Morse, Swampscott, and Lloyd E. Shaw, Newburyport, Mass., assignors to Columbia Broadcasting System, Inc., Salem, Mass., a corporation of New York

Application August 18, 1951, Serial No. 242,547

10 Claims. (Cl. 141—65)

This invention relates in general to exhaust systems and in particular to protective devices for use in such systems.

In the manufacture of electronic tubes as well as in other arts, when it is desired to exhaust the air from a system, pumps of various types are employed. Where the degree of vacuum desired is not great, a straight mechanical system may be used. To achieve lower pressure a diffusion pump is often inserted between the mechanical pump and the system to be exhausted.

Where high speed rotary exhaust machines are used, it has been found desirable to use an oil diffusion pump with each "head" or tube carrying element of the machine. The degree of vacuum, and speed of pumping are enhanced by such an arrangement, but several problems are presented when such a system is used. One difficulty encountered is the fouling of the jets of the diffusion pump by particles of glass which often find their way into the system. When breakage occurs, glass fragments are drawn into the pump and improper operation or failure of the pump may result. Even apart from breakage, it sometimes happens that tiny glass particles are present in the tubes being evacuated. Although these particles may be quite firmly lodged within the tubes, the pumping action is often sufficient to draw them from the tubes into the pump with serious results obtaining.

An obvious device for preventing these particles from reaching the pump is a trap of some type placed in the line between the tube and the pump. In the past, such traps usually took the form of a chamber having two lines connected thereto. The input line from the tube was placed below the level of the output line to the pump and the action of gravity was relied upon to prevent glass particles from entering the output line and reaching the pump. Such traps were fairly effective to remove heavy particles, but were quite inefficient in removing small, light particles which often were borne on the stream of gas being drawn through the chamber into the output line and thence to the pump. A further disadvantage attendant upon the use of such traps was the difficulty involved in dismantling them from the system to remove whatever larger particles may have been deposited within them.

Therefore, it is an object of the present invention to provide a trap for an exhaust system which adequately protects the pump being used in the system.

It is a further object of the present invention to provide a trap for an exhaust system which operates efficiently to remove solid particles of extremely small size and weight.

A still further object of the present invention is to provide a trap which may be easily dismantled from the system for cleaning purposes when necessary.

In general, the present invention consists in an exhaust system which utilizes a plurality of diffusion pumps, each of which has a substantially Y-shaped structure. This structure resembles the type of coupling which is known as a "Y branch," the Y being inverted with the stem directed upwardly toward the system being exhausted, the

2

straight leg leading downwardly to the intake line of a pump and the other or branch leg of the Y leading downwardly to a particle trap at an angle to the stem. Within the stem of the Y a tube is centrally supported in communication with the system being exhausted. This tube is bent to extend into the branch leg of the Y which contains the particle trap, wherein it is also centrally supported. Adjacent to the junction of the stem and branch leg of the Y, but within the branch leg, an upwardly facing aperture is formed in the tube. Gases being exhausted from the system pass through the tube, out the aperture and thence to the pump. Particles present in the system also pass through the tube, but by reason of their greater mass continue past the aperture and into a removable container within the trap. For a better understanding of the invention, together with other and further objects, features, and advantages, reference should be made to the following description which is to be read in connection with the accompanying drawings in which:

20 Fig. 1 is a perspective view of a portion of a rotary exhaust machine;

Fig. 2 is a schematic view of certain elements of the exhaust machine; and

Fig. 3 is a sectional view of the intake stack and trap of the diffusion pump.

Fig. 4 is a view, partially schematic, illustrating working elements of an exhaust machine.

Referring to Fig. 1 of the drawing there is illustrated in part a rotary exhaust machine. Such machines, as 30 in the present case, usually include a fixed plate having a plurality of axial openings symmetrically arranged in a circle. A rotatable plate usually similar to the fixed plate is lapped thereto, and a film of oil between the two plates aids in maintaining a vacuum-tight seal when the rotatable plate is moved relative to the fixed plate. The usual method of operation is to have mechanical pumps connected to certain of the openings in the fixed plate and electronic tubes placed in heads which are connected to the openings in the rotatable plate through diffusion 40 pumps. As the rotatable plate is indexed to place the proper openings thereof in register with the openings of the fixed plate being pumped, evacuation of the tubes results.

Referring now to Figs. 2 and 4 of the drawing, there is 45 shown schematically an electronic tube 1 carried in a head 19 on the rotary table 18 of an exhaust machine. The head 19 includes a length of rubber tubing into which the tubulation of the electronic tube may be inserted in vacuum tight relationship therewith. A pinch off member 50 may then be used to compress a portion of the rubber tubing to form a closure below the furthest point of penetration of the tubulation. Connected to the rubber tubing beneath the pinch off member is a metallic tube 2 which is also maintained in vacuum tight relationship 55 therewith. Metallic tube 2 passes into the intake stack of a diffusion pump 3 which may conveniently be suspended from the rotary table 18 as shown, thus permitting gases to pass from electronic tube 1 into the intake stack when the pinch off member is not set to compress the rubber tubing.

60 The outlet line 4 from diffusion pump 3 leads to rotary valve 5 which includes two plates having circularly arranged axial openings and sealed together in the manner discussed hereinabove. For purposes of simplification, a single opening 6 in rotatable plate 7 and a single opening 8 in fixed plate 9 are shown in Figs. 2 and 4. With these openings in register, gases from the diffusion pump 3 are drawn through rotary valve 5 thence through connecting line 11 to a mechanical pump 10.

65 Referring now to Fig. 3, there is shown in section a portion of diffusion pump 3. Tube 2 is inserted in the intake stack of the pump and a vacuum seal is provided

therebetween. The vacuum seal includes an externally threaded male member 13 at the top of the intake stack, cap 14 which has a central opening which clears tube 2 and has internal threads meshing with those of member 13. When cap 14 is tightened down on member 13, it bears upon a washer 15 which has a circular groove formed in its lower surface. The groove is matched to the end of the intake stack, and contains a rubber gasket 17 to maintain a vacuum tight seal between washer 15 and the top of the intake stack of diffusion pump 3. Washer 15 is welded to tube 2 and thus a seal is provided between tube 2 and the intake stack, the only inlet thereto being by way of tube 2.

At a point on the intake stack adjacent cap 14 there is shown an additional member 21 for trapping foreign matter coursing through tube 2. Member 21 is disposed at an angle to the intake stack and tube 2 is bent to enter member 21 at a central location. The end of member 21 is open, but a vacuum seal and cap 22 similar in structure to that on the intake stack closes off the open end. The cap in this case, however, has no opening and provides a solid vacuum tight closure. Tube 2 terminates in an open end spaced from the end of member 21. Adjacent the end of tube 2 is a barrier formed of a washer 23 welded to tube 2. A cylindrical container 24 having an opening formed at one end and being closed at the other end slidably fits within member 21. The opening in container 24 is of sufficient diameter to loosely fit over the end of tube 2 but not to clear barrier washer 23. A spring 25 is placed between the closed end of container 24 and cap 22 to cause container 24 to bear against barrier washer 23, maintaining its position over the end of tube 2. Above barrier washer 23, but disposed at a point within member 21 an aperture 26 is formed in tube 2. Thus, when diffusion pump 3 is drawing gas through the intake stack, foreign matter carried by the stream of gas from electronic tube 1 mounted above the intake stack passes through tube 2. At aperture 26, gases are diverted from tube 2 and into member 21, thence to the lower area of diffusion pump 3. Foreign matter, being of greater mass than that of the gas molecules, continues past aperture 26 and is collected in container 24.

Obviously, when it is desired to remove foreign matter which collects in container 24, removal of cap 22 is easily effected permitting access for removal and cleaning of container 24.

Although the foregoing specification describes the invention as embodied in an exhaust system for electronic tubes, such detailed limitation of the concepts is only for purposes of illustration of one form the invention may take. General application of the concepts to any system where it is desired to separate materials of different mass is believed to be within the scope of the invention, which should be limited only by the following claims.

What is claimed is:

1. An exhaust system comprising, a member to be evacuated, a pump having an intake stack, a tube connecting said intake stack to said member, and a trap connected to said intake stack, said tube penetrating said trap and terminating in an open end therein, said tube having a lateral aperture formed therein preventing the passage of solid material, but permitting the free flow of gases therethrough.

2. An exhaust system comprising a member to be evacuated, a pump having an intake stack and a tube connecting said intake stack to said member, said tube entering said intake stack and being bent at an angle to the longitudinal axis thereof, said pump drawing the contents of said member through said tube, said contents being confined by the walls of said tube, and defining a given path of travel, said tube having an aperture formed in a side thereof through which the gaseous portion of said contents is caused to flow, solid portions of said

contents continuing along said given path of travel through said tube.

3. An exhaust system comprising a member to be evacuated, a pump having an intake stack, a hollow trap having one end thereof attached to a side of said intake stack and communicating therewith through an aperture formed in the side thereof, a tube connecting said intake stack to said member, said tube being bent at an angle, a first portion of said tube passing through said intake stack and a second portion thereof entering said trap, said tube terminating in an open end within said trap and having an aperture formed in a side thereof at a point removed from said terminating open end but within said trap, and removable means for vacuum sealing the other end of said trap.

4. Apparatus for separating solid particles from a stream of gas comprising, a first chamber containing gas at a relatively high pressure and solid particles mixed therewith, a second chamber containing gas at a relatively low pressure, and a tube for passing said stream of gas from said first chamber to said second chamber, said tube having an aperture formed in a wall thereof and terminating in an open end within said second chamber, pressure within said second chamber being lower adjacent said aperture than at said open end, said stream of gas in said tube passing through said aperture and solid particles passing out said open end.

5. Apparatus for separating solid particles from a stream of gas comprising, a first chamber containing gas at a relatively high pressure and solid particles mixed therewith, a second chamber disposed beneath said first chamber, a pump for maintaining said second chamber at a relatively low pressure, a branch chamber connected to said second chamber, a tube having one open end in communication with said first chamber, and extending downwardly through said second chamber, the other open end of said tube being disposed within said branch chamber, said tube having an upwardly facing aperture formed in a wall thereof at a point within said branch chamber adjacent said second chamber, whereby said stream of gas passing through said tube is diverted through said aperture into said second chamber, solid particles continuing through said other open end of said tube into said branch chamber.

6. Apparatus for separating solid particles from a stream of gas comprising, a first chamber containing gas at a relatively high pressure and solid particles mixed therewith, a second chamber disposed beneath said first chamber, a pump for maintaining said second chamber at a relatively low pressure, a branch chamber having one end connected to said second chamber and depending downwardly therefrom, an open-ended tube having one end thereof in communication with said first chamber and extending downwardly through said second chamber into said branch chamber, said tube having an upwardly facing aperture formed in a wall thereof at a point within said branch chamber adjacent said second chamber, a container loosely fitted over the other end of said tube within said branch chamber, a removable cap for vacuum sealing the other end of said branch chamber, said cap maintaining said container in position over said other end of said tube whereby said stream of gas passing through said tube is diverted through said aperture into said second chamber, solid particles continuing through said tube into said container.

7. Apparatus for removing solid matter from the intake stack of a diffusion pump comprising, a tube vacuum sealed in said intake stack for permitting the entry of gases thereto, a trap having one end thereof joined to the side of said intake stack and communicating with the interior thereof by means of an aperture formed in a wall thereof, the longitudinal axis of said trap being at an angle to that of said intake stack, said tube being bent through an angle such that a portion thereof is coaxial with said trap, a container loosely fitted within said trap

and having an open end enclosing one end of said tube, and a removable cap for vacuum sealing the other end of said trap and for retaining said container within said trap, said tube having an aperture formed in a wall thereof whereby gases passing through said tube reach said intake stack through said aperture and solid foreign matter proceeds through said tube and into said container.

8. Apparatus for filtering solid matter from the intake stack of a diffusion pump comprising, a tube sealed in said intake stack for permitting the entry of gases thereto, a trap having one end thereof joined to the side of said intake stack and communicating with the interior thereof by means of an aperture formed in a wall thereof, the longitudinal axis of said trap being at a first angle to that of said intake stack, such that said trap depends downwardly therefrom, said tube being bent at a second angle equal to said first angle such that a first portion of said tube is coaxial with said intake stack and a second portion of said tube is coaxial with said trap, a barrier member of diameter larger than that of said tube welded thereto at a point within said trap, an upwardly facing aperture being formed in the wall of said tube above said barrier member but within said trap, a container having an open end of diameter larger than that of said barrier member loosely fitted within said trap with the open end thereof enclosing the open end of said tube and abutting said barrier member, and a removable cap for vacuum sealing the other end of said trap and for retaining said container in position whereby gases passing through said tube are diverted through said aperture formed therein and foreign solid matter continues through said tube into said container.

9. An exhaust system comprising, a rotary exhaust machine including a first rotatable plate having a plurality of axial openings formed therein symmetrically disposed in a circle adjacent the periphery thereof, a second fixed plate disposed beneath said first plate and having a similar plurality of axial openings formed therein about and adjacent the periphery thereof, said openings in said first plate being in register with those of said second plate, a plurality of diffusion pumps each having an intake stack and an outlet line, means for connecting each of said outlet lines to one of said openings in said first plate, a rotary table having a similar plurality of heads and adapted to rotate with said first plate, a similar plurality of tubes each connecting one of said heads to one of said intake stacks and each being bent at an angle to the longitudinal axes thereof at a point remote from the point of entry, a downwardly depending trap member having one end thereof connected to the side of said intake stack through an aperture formed therein, said tube entering said trap member and terminating in an open end adjacent the other end of said trap member, said tube having an upwardly facing aperture formed in a wall thereof at a point adjacent the bend in said tube between said aperture and said terminating open end, whereby gases issuing from said head are drawn through said tube and out said aper-

ture to the intake stack of said diffusion pump, solid particles being carried through the terminating open end of said tube and deposited in said other end of said trap member.

5 10. An exhaust system comprising, a rotary exhaust machine having a rotary table having a plurality of spaced heads disposed about and adjacent the periphery thereof, a first rotatable plate having a similar plurality of symmetrically arrayed axial openings formed therein, a similar plurality of diffusion pumps connected between said heads and said openings in said first plate, a second fixed plate disposed beneath said first plate in vacuum tight relationship therewith and having a similar plurality of symmetrically arrayed axial openings formed therein, said openings in said first plate being in register with those of said second plate, means for indexing said first plate relative to said second plate to bring consecutive ones of said openings in said first plate into register with those of said second plate, said plurality of diffusion pumps including intake stacks disposed beneath said rotary table, means for separately connecting each of said intake stacks to one of said spaced heads of said rotary table, said last-mentioned means each including a tube communicating with one of said plurality of openings in said second plate, each of said intake stacks having an aperture formed in a side thereof, hollow open ended members of cross-sectional dimensions substantially similar to those of said intake stacks, one end of each of said hollow members being connected at an angle to each of said intake stacks and depending downwardly therefrom, the open end of each of said hollow members and the aperture of each of said intake stacks forming a mutual opening therebetween, said tube being bent to enter said hollow member at a central point and to follow the longitudinal axis thereof, said tube terminating in an open end adjacent the other end of said hollow member, a cap threadably attached to said other end of said hollow member in vacuum-tight relationship therewith, a barrier washer attached to said tube at a point adjacent the termination thereof, said tube having an upwardly facing aperture formed in a wall thereof at a point above said barrier washer but within said hollow member, whereby gases issuing from said heads are pumped through said tube and out said aperture to the intake stack of said diffusion pump, particles of foreign matter being carried through said tube and deposited in said hollow member adjacent said cap.
